FIBER TREATMENT

Hughes L. Siever, Keyser, W. Va.

Application December 20, 1933, Serial No. 703,241

9 Claims. (Cl. 19—66)

The invention relates to the application of liquids to textile fibers and particularly cotton in the course of its manufacture into yarn, either for conditioning it for such manufacture or for imparting color or some other property thereto. Current methods of applying liquids to textile fibers involve the use of spraying devices and the like, and are subject to the objection that the surfaces of the apparatus wherein the textile is being worked or being handled, become wetted by the liquid and this not only interferes with the manufacture process, slowing down production, but also represents a waste of the liquid amounting in some cases to a substantial loss.

This invention provides a practical way to apply the treating liquid so that there is no contact thereof with the textile apparatus and so that the waste referred to is avoided and better and closer regulation made possible and other advantages also obtained as will presently become apparent.

According to this invention the treating liquid, which is by preference a light mineral oil of lubricating property or a liquid not too quickly drying, is delivered to an applicator device of suitable form and transferred therefrom to the cotton by the wiping action of the latter thereon as it advances into, through or from a textile machine. Preferably the oil or liquid is wiped off by the advancing cotton as the latter converges into a trumpet or other condensing instrument and by that part only of the cotton which is presently to form the interior part or core of the resultant delivery. Thus disposed the liquid is immediately enveloped or wrapped up in the larger mass of unwetted fibers where it remains until by further workings or otherwise it has become spread out in and taken up by them, imparting to them the desired properties. The amount thus applied is gauged according to the amount of stock and the ultimate liquid percentage desired for each fiber, and in consequence there is no excess or external wetness, to wet the machinery at any stage of manufacture and hence no difficulty in maintaining an exactly constant percentage of liquid in the product. Though not limited to oil the invention is peculiarly related thereto, since so far as I am aware in no other way can slowly or non-vaporizing liquids be so efficiently applied to permeate textile fabrics.

Practically all animal and vegetable fibers are hygroscopic and according to their own individual characteristics will absorb their normal amount of moisture, under certain humid con-

ditions. Since this invention primarily concerns cotton, this fiber will serve to illustrate the point in view. Normally, cotton fiber contains approximately 8% of water. When in this approximate condition, it is considered ideal for manufacturing purposes. Due to its hygroscopic nature it is difficult to maintain this moisture. Just as the fiber will absorb moisture under normal conditions, so will it give it up under abnormal conditions.

For the purpose of manufacturing the raw cotton into spun yarn through all the processes in a cotton manufacturing plant, it is desirable to keep the fibers at or near the normal content of moisture, because in this state the staple is soft, pliable, and the minimum friction results. If it becomes dry the fibers become brittle, break, flare out and are uncontrollable. In dry climates nature does not provide a constant humid condition and artificial means must be used to humidify the plants. The variations in climatic changes are so pronounced from day to day, that even the best artificial systems of humidifying are not capable or dependable to assure the best manufacturing conditions. Therefore, from a manufacturing standpoint, humidification may be considered nothing more or less than lubrication, inasmuch as it provides a condition of working the fibers into yarn and since the object of this invention is to facilitate the machining of these delicate fibers, the problem of lubrication falls within this scope.

Humidity refers to the amount of water vapor in the atmosphere. Absolute humidity means the actual density of water vapor regardless of its temperature or whether or not the air is saturated. Relative humidity is the ratio of the weight of vapor actually existing at the same temperature. Saturated air has a relative humidity of 100%.

To maintain a relative humidity in rooms and large cotton mills, and particularly at the point the fiber is actually throwing off its moisture, as in the drawing, intermediate roving frames, spinning frames, is almost impossible and fluctuations in the moisture content are constant and will vary throughout the mill in spite of all natural and artificial humidity. It is an object of this invention to displace the necessity and expense of humidification, by a satisfactory and suitable fixed lubricant, capable of remaining with the fiber throughout all the manufacturing processes, thus eliminating artificial humidification.

I am aware that certain methods are in use

for oiling the stock prior to the carding process, but the carding process being such a close, effective combing system composed of approximately 500 square feet of metallic wire, will not permit sufficient amounts of a fixed lubricant to be applied until the stock has passed the cards. Cotton manufacturers claim little or no humidity is required up to the point of converting the stock into the first sliver, because prior to this point manufacturing is a matter of cleaning the fiber, by rough shaking, tumbling, beating and picking, whereas, the drier the stock the better it cleans, therefore, humidity or lubrication is not considered essential and is avoided more or less. Up to the first sliver the fibers are more or less in a criss-cross formation, but from the sliver on the manufacturing is a problem of parallelism of individual fibers, while thereafter, the processes of drawing the fibers parallel causes friction to set up, as the drawing proceeds until spun into the finest of yarns. Friction creates static electricity, the stock becomes dry, the fibers flare out and become unruly and manufacturing becomes difficult unless lubrication is provided. It is another object of my invention to apply a suitable fixed lubricant in the central portion of the original or card sliver or subsequent slivers capable of conditioning the fibers to meet all the requirements of humidity. By a fixed lubricant is meant a nonoxidizable, non-conducting oil or liquid unaffected by atmospheric variations of climate, capable of spreading by permeation, throughout the mass of cotton, by contact in drawing the fibers parallel to each other through successive steps until spun into yarn. The object of placing the liquid in the center of the first sliver is necessary to insure permeation to start equally in all directions and to enclose the liquid constantly or alternately but centrally to effect the best distribution in subsequent drawing processes. I have found that by this method static electricity is practically eliminated and proper lubrication is provided, thus the expense of artificial humidification is not essential.

While the effect above described can be brought about in various kinds of textile machines, it is illustrated for the purpose of this disclosure as produced by treatment of cotton in an ordinary cotton card.

In the accompanying drawing, Fig. 1 is a general elevation, partly sectioned.

Fig. 2 a larger section of the trumpet and applicator, and

Fig. 3 a section on line III—III of Fig. 2.

The card fleece delivered by the doffer comb 1 is gathered into a trumpet 2 and drawn there-through by the calender rolls 3 from whence it is taken upwards by the coiler head 4, as a card sliver 5, and coiled into the sliver can 6, all in the usual manner. The applicator in this case is a slender tube 7 the delivery end of which is bent or directed inwards parallel to the path of the fiber and towards or into the mouth or entrance of the trumpet 2 and about on its central axis or so as to have contact only with that part of the gathering fleece which forms the center of the sliver. Preferably the open end of the tube is well within the trumpet as indicated so that the fibers wipe it with some pressure. It is supplied with the liquid through a glass sight tube 8 from a constant level receptacle or float chamber 9, the latter being connected to a larger supply source. By means of the needle valve 10, which constitutes a drip-

regulator and in virtue of the constant head afforded thereto by the float-controlled supply, the liquid flow into the tube can be nicely regulated to any predetermined number of drops per minute, observable in the sight tube. Thus a constant supply is maintained in and at the end of the tube which is constantly being wiped off by the fibers as they move into the trumpet. Those fibers which immediately contact with the wetted end of the tube are more or less soaked and overloaded with the oil, but the immediate squeezing effect of the trumpet and calender rolls 3 which is followed also by that of the coiler-head rolls tends to distribute such oil, thus immediately starting its outward permeation into the surrounding fibers. The progress or rate of permeation thereafter depends to some extent on the nature of the treating liquid, but with the percentage needed for normal working requirements with any liquid, there is no danger that the surfaces of the textile machine or of the sliver cans or other holders will become wetted or appreciably soiled with the liquid. Final distribution of the liquid is accomplished by the doubling and drawing, or evening, processes which normally follow the card, as will be understood and which uniformly distribute the liquid to all the fibers. With non-vaporizing liquid the process is not ordinarily complete until the subsequent workings have distributed the liquid; with vaporizing liquids such as water, ether, alcohol the mere lapse of time may suffice to complete it.

The invention further consists in and comprehends the principle of internally applying treating liquids, in the manner described or otherwise, when such liquids are dyeing or coloring media, because the internal application of a dye to a sliver, as I have discovered, is an excellent way of coloring a yarn during its manufacture and affords a notable saving of labor, dye and apparatus as compared to existing practice. When the treating liquid is a dye, it is best if it is oily or slow-drying, because it is thus best distributed to the rest of the fibers, for the production of a uniform color. When applied at the card, the ultimate shade or color is achieved when complete distribution of the liquid, has occurred as the result of the evening processes carried out as usual in the drawing frames, or in the slubbers.

The treating liquid whether a dye or not, can be applied at other stages of manufacture than the card and at successive stages if desired and if more liquid is required than can be delivered in one point. Obviously it can be applied in any textile-working machine where fibers converge in a fleece, lap, sliver or roving form into a condensing or gathering instrument and emerge therefrom as a compound delivery or in a compound state. In all such cases whether it be a comber, draw or roving frame an applicator tube similar to that shown herein can be availed of for locally wetting those fibers which make the center of the compound delivery and this will in general be found to be the most practical form of application.

When many machines are at work it is desirable that each of them be equipped with its own drip regulator device such as the needle valve in the present case or its equivalent and also with the sight tube or its equivalent, to the end that exact regulation of supply may thus be made at each machine affording maximum economy and uniformity of product.

I claim:

1. The method of treating textile fibers which comprises delivering liquid constantly to an applicator, conducting a fleece or band of the fibers over such applicator in wiping contact therewith and folding such band so that the wetted portion is in the interior.
2. The method of applying a treating fluid to textile fibers which comprises moving the fibers through a condensing instrument, depressing the central portion of the fibers by means of a fixed applicator through which the fluid flows and whereby the fluid is wiped from the applicator by the moving fibers and deposited in the central portion of the fibers.
3. The method of applying a coloring fluid to textile fibers which comprises delivering the fluid to an applicator, conducting a fleece or band of the fibers past such applicator in wiping contact therewith and folding such fleece or band so that the colored portion is on the interior.
4. In apparatus for treating textile fibers, the combination of a fiber conducting trumpet, means for passing the fibers through the trumpet, an applicator tube extending into the fibers and wiped thereby and having its outlet inside the trumpet entrance, and means for supplying liquid to said tube.
5. In apparatus for treating textile fibers, the combination of a fiber condensing instrument, an applicator tube having an open delivery end extending into the fibers and wiped thereby, said delivery end being disposed within the condensing instrument.
6. That method of treating textile fibers which

comprises delivering a liquid to an applicator and conducting said mass of fibers past said applicator in wiping contact therewith and folding said mass of fibers so that the applied fluid is on the interior of the mass.

7. The method of applying a treating fluid to a web of textile fibers as it emerges from a carding machine which comprises forming the web into a sliver and causing the treating fluid to drip onto the mass from above the mass as it is being condensed and before it reaches sliver stage.

8. In a machine for treating textile fibers having means for advancing the fibers in mass formation, the combination with a tubular applicator having its discharge outlet located so as to be embedded within and substantially surrounded by the advancing mass of fibers, a liquid supply source adapted to deliver liquid through said outlet in solid as distinguished from atomized form and means for regulating such delivery relative to the speed of the advancing fibers to confine the immediate moistening action to the interior of the mass.

9. In a machine for processing textile fibers having means for advancing the fibers in mass formation as distinguished from sliver or strand form, the combination with an applicator having its discharge outlet located substantially in the path of and wiped by the advancing mass of fibers, a liquid supply source adapted to deliver liquid through said applicator, and means for regulating such delivery relative to the speed of the advancing fibers.
